UNITED STATES PATENT OFFICE

CHARLES BLAMFIELD, OF BOSTON, MASSACHUSETTS

FIRE KINDLER

Application filed March 10, 1930. Serial No. 434,683.

My present invention relates to fire kindlers and more particularly to fire kindlers especially adapted for kindling fires in fire places, camp fires, and the like.

5 My present novel kindler comprises a piece of wood or other combustible material, having affixed to one face thereof a layer of material such as burlap, duck, bagging, or the like, said layer of material being impregnated 10 or saturated with a highly combustible substance, such as paraffin, I having found that paraffin produces the best results when utilized in conjunction with this kindler.

Another feature of the invention resides in 15 the provision of a pin on said kindler adapted to penetrate the piece of wood to which the kindler is attached, this pin being foldable out of operative position to lie flat against the face of the kindler, thus facilitating packing, 20 shipping and handling.

Another object of the invention is the provision of means whereby two or more kindlers may be united to produce a kindler of greater size, in the event that the same should be 25 needed.

It is essential, when utilizing these kindlers, that the same be spaced a proper distance from the surface of the fire wood to which it is attached. If too slight a space is provided 30 between the kindler and the fire wood, the flame produced by the saturated layer will be smothered, and if the space provided is too great, the fire or flame will be confined to the kindler and will not ignite the fire 35 wood.

A further and important object of the present invention, therefore, is the provision of a spacing guide, which may be made a part of the attaching pin or may be a separate element. The guide is also preferably foldable 40 to lie flat against the surface of the kindler, thus obtaining the same advantages as above briefly described for the pin.

When the pin and guide are in operative 45 position, the end of the guide will be spaced a sufficient distance below the point of the pin to enable said pin to effect a firm attachment of the kindler to the fire wood. The length of said guide will also be such that 50 when the pin has been inserted into the fire

wood and the guide has come in contact with said wood, just the proper space for most efficient igniting and combustion will be provided.

Another object of the invention resides in 55 the provision of a rabbet along the bottom inner edge of the kindler, the bottom edge of the saturated layer projecting over this rabbet and being preferably flush with the lower edge of the block or piece to which it 60 is attached. Said lower edge of the saturated layer is also preferably frayed, for instantaneous ignition upon the application of a lighted match thereto, the rabbet permitting the admission of sufficient air to the 65 said frayed edge to insure igniting thereof.

These kindlers are preferably constructed approximately three inches by two inches by one-half inch, but these sizes are for convenience only, and I am not in the least limited to any particular size.

My present kindler is simple to manufacture, economical, and simple to use, and takes the place of the usual kerosene swabs, as well as eliminating the use of light kindling 70 wood, shavings, and the like.

The quantity of paraffin or other combustible substance utilized to impregnate or saturate the layer of burlap, or the like, need not be a considerable amount, as by properly spacing the kindler relative to the wood to be ignited, only a slight amount of this paraffin is essential. The proper relative spacing of the kindler and the piece of wood to which it is attached, also, will result in 80 maintaining a hot spot that will keep the flame alive even after the paraffin or other combustible substance is consumed. It will thus be seen that the proper spacing of the kindler, and the means for effecting or insuring this spacing, is an important element 85 of my invention.

Other features of the invention consist in the particular construction of the kindler and the retaining means for the folding pin 90 and spacing guide.

The above and other objects and features of the invention, details of construction, and advantages, will be hereinafter more fully pointed out, described, and claimed.

I believe that the kindler above briefly described is novel, and have, therefore, claimed the same broadly in this application.

Referring to the drawings, illustrating a preferred embodiment of the present invention,

Fig. 1 is a front elevation of my novel kindler;

Fig. 2 is a side elevation thereof;

10 Fig. 3 is a vertical sectional view on the line 3—3 of Fig. 1;

Fig. 4 is an end elevation of said kindler;

Fig. 5 is a side elevation of my novel kindler attached to a piece of firewood to be 15 ignited thereby; and

Fig. 6 is a perspective view, partly broken away, illustrating the method of uniting two or more of my novel kindlers.

Referring now to the drawings, for a particular description of the invention, its construction, assembly and operation, 1 designates a wooden block, which is preferably used as the base of my kindler, the face 2 of said block being preferably coated with 25 a combustible substance such as paraffin.

Thereupon a strip or layer 3 of suitable material, such as bagging, burlap, or duck, is applied to the coated face 2 and pressed thereon. The strip 3 is saturated or impregnated with a suitable readily combustible substance, preferably paraffin, and the pressing of the strip 3 on to the face 2 will effect a union thereof, but to insure retention of the strip 3 on the block 1 I may utilize a 35 tack 4, or other holding device.

A groove 5 is provided in the block 1, preferably extending through the length thereof, for facility of formation, and lying in said groove 5 is a strip of wood 6 having recesses 40 7 formed at each side thereof at a suitable point, and also having a recess 8 extending transversely across the bottom of said strip. Seated in the groove 5 is a member 9, said member being located in the recess 8 and held 45 in said groove 5 by the strip 6. The member 9 has a pair of arms 10, and extending from said arms, at approximately right angles thereto, is a pin or prong 11, and a spacing guide 12 of less length than said prong. The 50 member 9 functions as a pivot, so that the prong 11 and guide 12 may be swung from folded position, as illustrated in Fig. 3, to open or operative position, as illustrated in Fig. 2, the recesses 7 in the strip 6 permitting 55 this tilting or pivoting action.

When the guide member 12 and prong 11 are folded, as illustrated in Fig. 3, the device is compact and easily handled for packing and shipping, the prong 11 and guide 12 being 60 swung or pivoted to operative position when it is desired to use the kindler. The bottom edge 13 of the layer 3 is frayed, the said frayed edge being substantially flush with the bottom edge 14 of the block 1, and 65 a rabbet 15 is formed in said block adjacent

to said edge 13. This rabbet will permit the admission of sufficient air around the bottom edge of the strip or layer 3 to facilitate ignition thereof.

In Fig. 5 I have illustrated the method of using my novel device, wherein the prong 11 has been inserted into a stick of wood 16, further penetration of the prong 11 being prevented by the blunt end of the guide member 12. The length of this spacing guide 12 is predetermined for the most efficient spacing of the kindler from the wood 16. Thereupon, when a lighted match 17 is applied to the frayed edge 13, combustion of the kindler will ensue, the flame first traveling up the layer 3 and creating a hot spot against the face of the wood 16, which will ignite the wood 16 and which hot spot will be retained even after the layer 3 has been consumed.

The proper spacing of the kindler relative to the surface of the wood 16 is highly important, and by the use of the guide 12 all guess work is eliminated, thus insuring proper operation of the kindler and the obtaining of the best results therefrom.

While I have illustrated the prong 11 and guide 12 as integral, it will be appreciated that these may be made two separate members, if desired.

In the event that it is desired to utilize more than one kindler, I provide a groove 18 in each kindler, and thus two or more kindlers may be united by means of a pin 19 seated in said grooves, as clearly illustrated in Fig. 6.

Each layer or strip 3 is provided with an aperture 20, through which the members 11 and 12 project.

The advantages, benefits, and utility of my novel kindler will be readily apparent.

While I have necessarily described my present invention somewhat in detail, it will be appreciated that I may vary the size, shape, and arrangement of parts within reasonably wide limits, without departing from the spirit of the invention.

My invention is further described and defined in the form of claims as follows:

1. A fire kindler comprising a block of combustible material, a layer of porous material attached to one face of said block, said layer being saturated with suitable readily combustible substance, means to attach said kindler to a piece of wood to be ignited thereby, and means to space said kindler a predetermined distance from said wood, said attaching means and said spacing means being foldable substantially flat against the surface of said kindler.

2. A fire kindler comprising a block of combustible material, a layer of porous material attached to one face of said block, said layer being saturated with suitable readily combustible substance, means to attach said kindler to a piece of wood to be ignited there-

by, and means to space said kindler a predetermined distance from said wood, each kindler being provided with means whereby two or more kindlers may be united.

5 3. A fire kindler comprising a block of combustible material, a layer of porous material attached to one face of said block, said layer being saturated with suitable readily combustible substance, means to attach said kindler to a piece of wood to be ignited thereby, and means to space said kindler a predetermined distance from said wood, the bottom edge of said porous layer being substantially flush with the bottom edge of said 10 block, said block having a rabbet therein adjacent to the bottom edge of said layer.

15 4. A fire kindler comprising a block of combustible material, a layer of porous material attached to one face of said block, said 20 layer being saturated with suitable readily combustible substance, means to attach said kindler to a piece of wood to be ignited thereby, and means to space said kindler a predetermined distance from said wood, said attaching means and said spacing means being 25 integral and simultaneously foldable substantially flat against the surface of said kindler.

30 5. A fire kindler comprising a block of combustible material, a layer of porous material attached to one face of said block, said layer being saturated with suitable readily combustible substance, a groove in said block, a member seated in said groove, a prong on 35 said member for attaching said kindler to a piece of wood to be ignited thereby, a spacing guide on said member to space said kindler a predetermined distance from said wood, and a retaining strip seated in said 40 groove to prevent separation of said member from said kindler.

45 6. A fire kindler comprising a block of combustible material, a layer of porous material attached to one face of said block, said layer being saturated with suitable readily combustible substance, a groove in said block, a member seated in said groove, a prong on 50 said member for attaching said kindler to a piece of wood to be ignited thereby, a spacing guide on said member to space said kindler a predetermined distance from said wood, and a retaining strip seated in said groove to prevent separation of said member from said kindler, said retaining strip being 55 provided with means whereby said prong and said guide may be folded substantially flat against the surface of said kindler.

60 7. A fire kindler comprising a block of combustible material, a layer of porous material attached to one face of said block, said layer being saturated with suitable readily combustible substance, a groove in said block, a member seated in said groove, a prong on 65 said member for attaching said kindler to a piece of wood to be ignited thereby, a spac-

ing guide on said member to space said kindler a predetermined distance from said wood, and a retaining strip seated in said groove to prevent separation of said member from said kindler, said retaining strip being 70 provided with means whereby said prong and said guide may be folded substantially flat against the surface of said kindler, the bottom edge of said porous layer being substantially flush with the bottom edge of said 75 block, said block having a rabbet therein adjacent to the bottom edge of said layer, whereby air may be admitted around the bottom edge of said layer to facilitate combustion.

80 In testimony whereof, I have signed my name to this specification.

CHARLES BLAMFIELD.
